UNITED STATES PATENT OFFICE

168,329

MEASURING TAPE

Sidney Blum, Forest Hills, N. Y., assignor to
Oxwall Tool Co., Ltd., Oxford, N. J., a corpora-
tion of New York

Application August 21, 1952, Serial No. 21,155

Term of patent 14 years

(Cl. D52—1)

To all whom it may concern:

Be it known that I, Sidney Blum, a citizen of the United States, residing at Forest Hills, Long Island, State of New York, have invented a new, original, and ornamental Design for a Measuring Tape, of which the following is a specification, reference being had to the accompanying drawing, forming a part hereof.

Fig. 1 is a perspective view of a measuring tape looking at one side, showing my new design.

Fig. 2 is a perspective view looking at the other side thereof.

Fig. 3 is an end view thereof.

I claim:

The ornamental design for a measuring tape, as shown.
